FUEL BURNER

Harry Cowan, Akron, Ohio, assignor to The Babcock & Wilcox Company, Rockleigh, N. J., a corporation of New Jersey

Application April 26, 1947, Serial No. 744,083

7 Claims. (Cl. 299—58)

1

This invention relates in general to the construction and operation of liquid fuel burners, and more particularly, to the construction and operation of the supply connections for liquid fuel burners of the fluid atomizing type.

Liquid fuel burners are normally mounted in a position in a furnace wall where at least their discharge ends are subject to the high furnace temperatures. In operation, the flow of liquid fuel through the burner tends to maintain the burner metal at a safe operating temperature, but when the liquid fuel supply is off, as when installing or changing burners, the burner metal is liable to be overheated if exposed for even a relatively short time to high temperatures before it is withdrawn or the fuel supply restored. There is also normally a liquid fuel residue left in the fuel passage when the fuel supply is cut off, and this residue tends to char or coke, and thus wholly or partly clog the fuel passage, requiring the burner to be dismantled for cleaning. Coking is particularly liable to occur when the liquid fuel is of a relatively viscous type, such as bunker C fuel oil, tar, or pulp residual liquid. When such fuels are to be introduced into the furnace in a finely atomized condition, the atomization is usually effected by an atomizing fluid, such as steam, or in some cases air, at a pressure higher than that of the liquid fuel and flowing through the burner in a stream surrounding or within the burner fuel passage to a point where the atomizing fluid impinges on the liquid fuel stream to atomize the same.

In accordance with the present invention, the atomizing fluid and liquid fuel supply connections of a liquid fuel burner of the fluid atomizing type are constructed and arranged to automatically provide a flow of atomizing fluid through the liquid fuel passage of the burner whenever the liquid fuel supply to the burner is cut off, to not only cool the burner metal but also simultaneously purge the liquid fuel passages of the burner and supply connection of any fuel residue therein.

In the drawings:

Fig. 1 is an elevation partly in section of a liquid fuel burner assembly mounted in a furnace wall;

Fig. 2 is a front view of the burner supply connections;

Fig. 3 is a detail of the burner discharge end; and

Figs. 4, 5 and 6 are partly diagrammatic views showing different operating positions of the control mechanism.

2

In the drawings, the invention is illustrated as embodied in the supply connections of a liquid fuel burner 10 of the fluid atomizing type removably mounted in a clamp 11 of a burner 5 mounting 12 positioned in an opening in a vertical wall 13 of a water cooled furnace. As shown in Fig. 3, the fuel burner 10 is of the type disclosed in the copending application of James Fletcher, Serial No. 744,891, filed April 30, 1947, and includes a central pipe 15 surrounded by a spaced pipe 16, thus forming an inner fuel passage surrounded by an annular steam passage. The fuel pipe 15 opens into a transversely elongated slot of a sprayer plate 17 into which a series 10 of steam passages 18 open at points intermediate the slot length. With this construction, the liquid fuel stream is impinged on by a multiplicity of steam jets at a higher pressure, atomizing the liquid fuel into a finely divided condition. A coupling 20 containing steam and liquid fuel inlets 21 and 22 is detachably connected to the burner steam and fuel passages respectively. The steam inlet 21 is connected through a nipple 23, union 24, and elbow 25 to an upwardly curving 15 flexible steam hose 26. The fuel inlet 22 is similarly connected through a nipple 27, union 28, and elbow 29 to an upwardly curving flexible fuel hose 30.

The steam hose 26 is connected through a coupling to a discharge opening of a three-way three-port rotary plug valve 34. The inlet opening of the valve 34 is connected by a pipe 35 to a subjacent steam supply header 36. The fuel hose 30 is connected to a discharge opening of a three-way two-port rotary plug valve 40, the inlet opening of which is connected through a pipe 41 to a subjacent liquid fuel supply header 42. The arrangement of the valves 34 and 40 at the high point of the burner assembly facilitates 20 drainage away from the valves to the associated conduits. The rotary plugs or cocks of the valves 34 and 40 are simultaneously rotated by a common yoke 45 detachably connected thereto and having an operating lever 46. In accordance 25 with the invention, the valves are connected by a sectional by-pass pipe 49 to permit a controlled flow of steam from the valve 34 through the pipe 49 and valve 40 to the liquid fuel hose 30. With the pipe connections illustrated, the steam and liquid fuel supply sections of the burner assembly 30 can be separately dismantled.

In Figs. 4, 5 and 6, the arrangement of the ports of the valves 34 and 40 are indicated for different positions of the operating lever 46.

Fig. 4 shows the lever in a vertical "up" position

when the burner is "off," the valve ports being then arranged so that the flow of both steam and liquid fuel is cut off. As the lever is moved downwardly 90° to a horizontal position, the valves 34 and 40 are rotated so that steam will flow through the valve 34 not only to the steam hose 26 but also through the by-pass pipe 49 through the valve 40 to the liquid fuel hose 30, the fuel supply being cut off. In this position the fuel burner will have a flow of steam through both the inner fuel pipe 15 and the surrounding steam pipe 16. As shown in Fig. 6, as the handle is turned 90° to a vertical "down" position for the burner "on" position, the valves 34 and 40 are rotated so that the valve 34 cuts off the supply of steam to the by-pass pipe 49 and delivers steam only to the steam hose 26, while the valve 40 is rotated to close off the by-pass pipe and deliver liquid fuel from the fuel header 42 to the fuel hose 30. The lever movement is reversed when moving from the burner "on" position to the burner "off" position.

When for example, the fuel burner is to be installed in the mount 12, it is first positioned in the clamp 11 with its discharge end backed well out of the furnace. Before it is slipped down into its operating position, the lever 46 is turned to its horizontal or purging position so that steam will flow through both the steam and fuel passages of the burner. The burner is then slipped down in the clamp into its operating position and the valves turned to the burner "on" position shutting off the steam flow through the by-pass connection and opening the liquid fuel supply to the burner. In withdrawing the burner after use, the valve operating procedure is reversed, the valve lever being first turned to the purging position and the burner pulled back out of the furnace but not out of the clamp 11. The lever is then turned to the burner "off" position and the burner unclamped and removed from the burner mount.

The burner assembly described provides a relatively simple and low cost construction for insuring adequate protection of the burner from overheating and clean liquid fuel passages in the burner assembly whenever the burner is put into operation.

While in accordance with the provisions of the statutes I have illustrated and described herein the best form of the invention known to me, those skilled in the art will understand that changes may be made without departing from the spirit of the invention covered by my claims, and that certain features of my invention may sometimes be used to advantage without a corresponding use of other features.

I claim:

1. A liquid fuel burner assembly comprising a liquid fuel burner having a liquid fuel discharge passage and an atomizing fluid discharge passage therein, a liquid fuel supply conduit and an atomizing fluid supply conduit connected to said passages respectively, a three-way rotary valve in each of said conduits, an atomizing fluid by-pass passage independent of said conduits and directly connecting said valves, and means for simultaneously rotating said valves into successive operating positions, in one of which said valves are positioned to direct atomizing fluid from said atomizing fluid supply conduit through said by-pass passage to said burner liquid fuel discharge passage.

2. A liquid fuel burner assembly comprising a liquid fuel burner having a liquid fuel discharge

passage and a steam discharge passage therein, a liquid fuel supply conduit and a steam supply conduit connected to said passages respectively, a three-way three-port valve in said steam supply conduit, a three-way two-port valve in said liquid fuel supply conduit, a steam by-pass passage independent of said conduits and directly connecting said valves, and means for moving said valves into successive operating positions including an intermediate position in which said valves are positioned to direct steam from said steam supply conduit through said by-pass passage and liquid fuel supply conduit valve to said burner liquid fuel discharge passage.

3. A liquid fuel burner assembly comprising a liquid fuel burner having a liquid fuel discharge passage and steam discharge passage therein, a liquid fuel supply conduit and a steam supply conduit connected to said passages respectively, a three-way three-port rotary plug valve in said steam supply conduit, a three-way two-port rotary plug valve in said liquid fuel supply conduit, conduit means separate from said supply conduits forming a steam by-pass passage directly connecting said valves and providing continuously open communication therebetween, and common operative means for simultaneously rotating said valves into successive operating positions including an intermediate position in which said valves are positioned to direct steam from said steam supply conduit through said by-pass passage and liquid fuel supply conduit valve to said burner liquid fuel discharge passage, said valves in another of said positions cutting off the supply of liquid fuel and of steam to the respective burner discharge passages.

4. A liquid fuel burner assembly comprising a liquid fuel burner having a liquid fuel discharge passage and a steam discharge passage therein, a liquid fuel supply conduit and a steam supply conduit connected to said passages respectively, a three-way three-port rotary plug valve in said steam supply conduit, a three-way two-port rotary plug valve in said liquid fuel supply conduit, conduit means separate from said supply conduits forming a steam by-pass passage directly connecting said valves and providing continuously open communication therebetween, and common operating means for simultaneously rotating said valves into successive operating positions including an intermediate position in which said valves are positioned to direct steam from said steam supply conduit through the valve therein to both said burner steam discharge passage and said by-pass passage, and through said by-pass passage and said liquid fuel supply conduit valve to said burner liquid fuel discharge passage, said valves in other positions respectively opening up and cutting off the supplies of liquid fuel and steam to the respective burner discharge passages.

5. In combination with a liquid fuel burner having a liquid fuel discharge passage and an atomizing fluid discharge passage therein, a valved conduit structure comprising a pair of headers constituting a liquid fuel supply header and an atomizing fluid supply header respectively, a liquid fuel supply conduit and an atomizing fluid supply conduit connecting the respective headers of said pair to said passages respectively, a valve in each of said conduits, an atomizing fluid by-pass conduit directly connecting said valves and independently of said supply conduits providing continuously open communication therebetween, and valve operating means for

moving said valves simultaneously into different operating positions, in two of which positions said valves are positioned to shut off, and to open up, respectively, the supply of liquid fuel and atomizing fluid to said burner discharge passages respectively, and in a position intermediate said two positions said valve in said atomizing fluid supply conduit is positioned to direct atomizing fluid from said atomizing fluid supply conduit in part to said burner atomizing fluid discharge passage and in part to said atomizing fluid by-pass passage, while said valve in said liquid fuel supply conduit is positioned to shut off the supply of liquid fuel to said burner liquid fuel discharge passage and to direct atomizing fluid from said by-pass passage thereto.

6. In combination with a liquid fuel burner adapted to be adjustably positioned relative to a firing zone and having a liquid fuel discharge passage and an atomizing fluid discharge passage therein, a valved conduit structure comprising a pair of horizontally disposed stationary headers constituting a liquid fuel supply header and an atomizing fluid supply header, a liquid fuel supply conduit and an atomizing fluid supply conduit connecting said headers to said passages respectively, said conduits each having an inlet end portion extending upwardly from the corresponding header of said pair, a valve in each of said conduits disposed in said upwardly extending inlet end portion thereof, said valves having plugs rotatable about a common horizontal axis, an atomizing fluid by-pass conduit directly connecting said valves and independently of said supply conduits providing continuously open communication therebetween solely at elevations above said axis, and valve operating means engaging said plugs for simultaneous rotation thereof into successive oper-

ating positions, said supply conduits having flexible outlet end portions intermediate said valves and said burner discharge passages.

7. A liquid fuel burner assembly comprising a liquid fuel burner having a liquid fuel discharge passage and an atomizing fluid discharge passage therein, a liquid fuel supply conduit and an atomizing fluid supply conduit connected to said passages respectively, a three way valve in each 5 of said conduits, an atomizing fluid by-pass passage independent of said conduits and directly connecting said valves, and valve operating means for moving said valves simultaneously into different operating positions, in two of which positions said valves are positioned to shut off, and to open up, respectively, the supply of liquid fuel and atomizing fluid to said burner discharge passages respectively, and in a position intermediate said two positions said valve in said atomizing 10 fluid supply conduit is positioned to direct atomizing fluid from said atomizing fluid supply conduit in part to said burner atomizing fluid discharge passage and in part to said atomizing fluid by-pass passage, while said valve in said liquid fuel supply conduit is positioned to shut off the supply of liquid fuel to said burner liquid fuel discharge passage and to direct atomizing fluid from said by-pass passage thereto.

HARRY COWAN.
